BLOCK-SIGNALING SYSTEM AND SAFETY APPARATUS.

1,031,529.

Specification of Letters Patent. Patented July 2, 1912.

Application filed November 30, 1908. Serial No. 465,072.

To all whom it may concern:

Be it known that I, MARK CONRAD, a citizen of the United States, residing at Adrian, in the county of Lenawee and State of Michigan, have invented new and useful Improvements in Block-Signaling Systems and Safety Apparatus, of which the following is a specification.

This invention relates to block signaling systems adapted for use on steam or electric roads and designed to be entirely automatic in its operation for preventing head-on or rear-end collisions on single track lines or accidents at crossings and switches, thus dispensing with the usual telegraph and block offices with their operators and signal men and dispensing also with the train dispatcher.

The invention has for one of its objects to improve and simplify the construction and operation of signal systems of this character so as to be comparatively simple and inexpensive to manufacture and install, thoroughly reliable and efficient in use, and entirely automatic in operation.

Another object of the invention is the provision of a signal system in which each block has a semaphore, target or the like, at both ends, in connection with electrical devices and circuits whereby the signal at the far or leaving end of the block will be set to danger position a suitable period in advance of the operation of the signal at the entrance end of the block, both signals being held in danger position against the attraction of gravity by locking devices that are automatically released by electro-magnets connected in circuit as the train leaves the block.

With these objects in view and others, as will appear as the description proceeds, the invention comprises the various novel features of construction and arrangement of parts which will be more fully described hereinafter and set forth with particularity in the claims appended hereto.

In the accompanying drawings, which illustrate one embodiment of the invention, Figure 1 is a diagrammatic view of the system as applied to one block of a single track

line. Fig. 2 is a side view of the locking device for holding a semaphore in danger position. Fig. 3 is a detail sectional view of the locking device. Fig. 4 is a diagrammatic view of the track showing two trains thereon in a single block, together with the circuit connections. Fig. 5 is a diagrammatic view of a track switch showing means for grounding the third rail for the circuits of the emergency stopping system. Fig. 6 is a diagrammatic view of a crossing of two tracks showing the arrangement of the third rails or conductors.

Similar reference characters are employed to designate corresponding parts throughout the views.

Referring to Fig. 1 of the drawing, 1 and 2 designate the main rails of a track which is divided into blocks and at the ends of adjacent blocks are insulated rail sections *a* and *a'* in the opposite rails that are connected with the circuits of one block and in one of the rails at each end of the block is an insulated rail section *b* for connection with the circuits of adjacent blocks, as will be hereinafter explained.

At the ends of the blocks are signaling devices *A* and *B* arranged some distance inwardly from the ends of the block so that the signals will operate before a train reaches the signal and after it enters the block for the purpose of warning the engineer that the system is in perfect operation. The signals are operated and controlled in such a manner that the signal at the leaving end of the block will operate in advance of that at the entrance end so that by this means, the opposite end of the block will be guarded against the entrance of a train approaching in the opposite direction and thereby prevent a head-on collision. Each signal device comprises in the present instance a semaphore consisting of a vane or arm 3 for signaling by day and a colored glass or other target 4 for signaling by night, the semaphore being mounted to swing to and from danger position on a shaft 5. The arm or vane 3 is provided with a weight 3^a to overbalance the target 4 so that the semaphore will return to normal or

clear track position by gravity. The semaphore is moved to danger position by an electric motor M operatively connected with the shaft 5 in any suitable manner, so that 5 when the motor is energized, the semaphore will be raised from inclined to horizontal or danger position.

The semaphore is releasably held in the danger position by a locking device C, which 10 consists of a ratchet wheel 6 on the shaft 5 of the semaphore, with which cooperates a spring-pressed pawl 7 located adjacent the wheel to engage the teeth thereof for preventing the semaphore from dropping to 15 clear track position, said pawls being left out of Fig. 1 for clearness of illustration of adjacent parts. The pawl 7, as shown in Figs. 2 and 3, is mounted on an armature 8 of the pawl-releasing electro-magnet 9. The 20 electro-magnet is provided with yoke bars 10 on which is guided the central stem 12 of the armature, and on this stem is a spring 13 which bears against the collar 14 on the stem and against the yoke 11 to force the 25 pawl upwardly and hold it in engagement with the ratchet wheel 6.

At each motor M is a circuit closer consisting of a fixed contact 15 and a swinging contact 16 connected with the shaft 5 of 30 the semaphore and so arranged as to engage the contact 15 as the semaphore reaches danger position. By means of these circuit closers, the operation of one motor precedes that of the other motor, as will be described 35 hereinafter. In other words, the circuit of the motor for the semaphore at the leaving end of a block is closed automatically as the train enters the block and by the time the semaphore reaches danger position, the circuit closer thereof will close the circuit of the 40 motor for the semaphore at the entrance end of the block for operating such semaphore to indicate to the engineer of the approaching train that the system is in working order and that the semaphore at the leaving 45 end of the block has been raised to danger position; otherwise the circuit for the motor of the semaphore at the entrance end of the block would not be closed.

50 At each signal, a relay R is employed for closing the motor circuit of the opposite signal and the relays are energized by current derived from a generator or battery on the locomotive of the train, the source of 55 current being connected in any suitable manner by wheels with the rails of the track. As a train enters the block, the wheels will make contact with the rail section a' and the opposite grounded portion of the rail 1, 60 and current then flows from the source on the locomotive through the rail section a' , wire 17, relay R, wire 18, ground g , to ground g' , wire 19, rail 1, and back to the source of current on the locomotive. The 65 relay is thus energized and closes the armature

20 thereof which forms part of the switch S for closing the circuit of the motor for the semaphore at the end of the block. In each motor circuit is shown a battery 21, although, if desired, the current 70 may be derived from a power circuit extending along the railroad. When a train enters the block station A, the switch S of the relay at such station will be closed and current will pass from the battery 21 at the station B through the wire 22, the switch s, wire 23, brush 24 of the motor at the station B, motor M, brush 25, wire 26, switch S, wire 27, wire 28 which is connected with the opposite side of the battery 21 at the signal 75 B. The motor at the signal B will thus be actuated so as to bring the semaphore to danger position. During this movement of the semaphore, the contact 16 of the circuit closer will engage the contact 15 so as to 80 connect the motor at the signal A in circuit with its battery. Current now flows from the battery 21 at the signal A through the wire 28, wire 27, thence to the opposite end of the block at the signal B, through the contacts 15 and 16 of the circuit closer at 85 such signal, through the wires 29 and 26, through the latter wire back to the signal A, brush 25 of the motor of the signal A, through the motor, brush 24, wire 23, switch 90 s, wire 22, and to the other side of the battery 21 from that to which the wire 28 is connected. It will thus be seen that the signal A will be thrown to danger position after the signal B has been operated to thereby 95 protect the train ahead and behind while in the block. When a train enters the block at the end where the signal B is located, the signals operate in reverse order to that above described. That is to say, the signal A will operate first as the train enters the block and then the signal B will be operated. 100 The signals will be held in danger position as long as the train is in the block and as the train leaves the block, circuits will be 110 established for energizing the pawl-releasing magnets 9 of both signals so that the signals can drop by gravity to clear position. Connected with each rail section a is a wire 30 that is connected to ground at 115 31 and included in this wire is an electro-magnet 32 for closing a switch s' , the movable element of which is mechanically connected with and insulated from the movable element of the adjacent switch s by a strip 120 33, so that the motor circuit of a signal will be opened as the switch s' closes. The switches s' are connected by wires 34 and 35 with the electro-magnets 9 of the pawl-releasing devices and current is supplied by 125 batteries 36. By the closing of either switch s' , the electro-magnets 9 will be simultaneously energized so as to retract the pawls 7 for thereby permitting the semaphores to gravitate to clear track position. 130

The current for energizing the electro-magnets 32 is derived from the generator or other source on the locomotive and as soon as the wheels on the locomotive contact with the rail section *a*, the current will flow from the one terminal of the generator on the locomotive through the rail section *a*, wire 30, electro-magnet 32, ground 31, ground *g*², wire 37, rail section 2 (if the train be entering the block at A), and back to the other terminal of the generator on the locomotive. As soon as the electro-magnet 32 becomes de-energized by the wheels passing off the rail section *a*, the switches *s* and *s'* will return to normal position.

Fig. 5 represents a diagram of a track switch of which 1 and 2 are the main rails, and 51 and 52 the rails of a siding or branch track, the switch points 53 being operated by a rod 54 connected with a switch stand 55 of any approved construction. When the switch points are thrown to open the switch, the third rail 41 will be connected to ground by a switch that includes a blade 56 on the switch-stand and contacts 57, the blade being connected to ground by a wire 58 and the contact 57 connected to the third rail by a wire 59. By this arrangement, the third rail of the main line will be connected in circuit as long as the track switch remains open, so that a train traveling on the main line will be brought to rest by its emergency stopping devices before the switch is reached. Fig. 6 is a diagram of a track crossing which shows the third rails 41 of both tracks electrically connected by a wire *w*, so that it will be impossible for two trains to approach the crossing at the same time, since the presence of two trains in the blocks of both tracks which intersect each other at the crossing, will close the motor circuits of the emergency stopping devices and thus bring the trains to rest in time to avoid an accident.

Having thus described the invention, what I claim is:—

1. In a block signal system, the combination of signals at the ends of the block, a motor for actuating each signal, circuits for the motors, devices controlled by the entrance of a train in the block for closing the circuit of the motor at the leaving end of the block, means for closing the circuit of the other motor by the movement of the signal at the leaving end of the block, locking devices for holding the signals in set position, switches for cutting the locking devices into and out of circuit and for opening and closing the motor circuits, an electro-magnet energized as the train leaves the block for operating the switches.

2. In a block signal system, the combination of separate signals, an electric motor for moving each signal to danger position

against the attraction of gravity, circuits for the motors, a relay for closing the circuit of the motor at the leaving end of the block, a circuit for the relay adapted to be completed by a train passing into the block, a circuit closer closed by the operation of the motor at the leaving end of the block for closing the circuit of the motor at the entrance end thereof, locking devices for holding the signals in set position, electro-magnets for releasing the said devices, a circuit for the electro-magnets, normally open switches in the last-mentioned circuit, and electrical means at the ends of the block adapted to be energized by the passage of the train out of the block for closing said switches to energize the releasing magnets.

3. In a block signaling system, the combination with a track having insulated sections and a train adapted to enter upon said insulated track sections, of a source of current carried by the train, means for connecting said source of current with said insulated sections a signal at the entering and at the leaving end of the block, an electric motor for each signal, a relay at each signal station for controlling the motor at the other station, partial circuits for the relays arranged to be closed by the entrance of a train on certain of said insulated sections, locking means for said signals, and circuits including releasing devices for said signal locking means arranged to be closed by the passage of a train over certain other of said insulated sections.

4. In a block signaling system, the combination with a track having insulated sections and a train adapted to enter upon said insulated track sections, of a source of current carried by the train, means for connecting said source of current with said insulated sections, a signal at the entering and at the leaving end of the block, an electric motor for each signal, a relay at each signal station for controlling the motor at the other station, partial circuits for the relays arranged to be closed by the entrance of a train on certain of said insulated sections, locking means for said signals.

5. In a block signaling system, the combination with a track having insulated sections and a train adapted to enter upon said insulated track sections, of a source of current carried by the train, means for connecting said source of current with said insulated sections, a signal at the entering and at the leaving end of the block, an electric motor for each signal, a relay at each signal station for controlling the motor at the other station, and partial circuits for the relays arranged to be closed by the entrance of a train on certain of said insulated sections.

6. In a block signaling system, the com-

bination with a track having insulated sections and a train adapted to enter upon said insulated track sections, of a source of current carried by the train, means for connecting said source of current with said insulated sections, a signal at the entering and at the leaving end of the block, an electric motor for each signal, and a relay at

each signal station for controlling the motor at the other station.

In testimony whereof I affix my signature in presence of two witnesses.
